UNITED STATES PATENT OFFICE.

JOHN A. TRAYLOR, OF DENVER, COLORADO.

ROTARY RUNNER FOR ROTARY AND CENTRIFUGAL PUMPS.

1,131,294.

Specification of Letters Patent. Patented Mar. 9, 1915.

Application filed June 17, 1913. Serial No. 774,173.

To all whom it may concern:

Be it known that I, JOHN A. TRAYLOR, a citizen of the United States of America, residing in the city and county of Denver and State of Colorado, have invented a new and useful Rotary Runner for Rotary and Centrifugal Pumps, of which the following is a specification.

My invention relates to improvements in 10 runners or impellers for centrifugal pumps; and the object of my invention is: to provide a rotary water lifting and driving runner for centrifugal pumps that is arranged and adapted to equalize the pressure of the water on each side of the runner and to do away with the end thrust on runners or the 15 necessity of double suction pumps. I attain this object by the mechanism illustrated in the accompanying drawings, in which:

20 Figure 1, is a side elevation of a rotary runner for use in rotary or centrifugal pump. Fig. 2, is an edge view of Fig. 1. Fig. 3, is a sectional elevation of my improved runner operatively mounted in its 25 casing, the runner and its casing as illustrated forming a rotary water pump.

Similar letters of reference refer to similar parts throughout the several views.

The commonly used form of runner 30 consists of a solid imperforate disk with blades on one side only. This construction leaves a flat plate surface on the back of the runner, which chambers a quantity of water that is under the same pressure as the water at the periphery of the runner, and as this chambered water has no connection with the suction, it exerts a constant pushing pressure on the runner toward the suction side of the 35 pump and forces the water into and through the stuffing box, and as the water usually 40 contains sand or other gritty material, it cuts the shaft and bearing, wearing them rapidly away. This thrust will be equal to whatever pressure would result from any 45 pressure of water in the discharge of the pump against the area at the back of the runner; for instance; if there happened to be 100 square inches of area back of this 50 runner, the pressure would be 100 times whatever the discharge pressure in the 55 pump happened to be, less the atmospheric pressure on the suction side of the pump.

The essential object of my invention is to 55 equalize the pressure on both sides of the runner, in pumps having a suction intake on only one side of the runner, and my in-

vention contemplates a runner having water lifting blades running from points adjacent to the hub of the runner to their ends, with open spaces between them, and consequently 60 without a flange center or central portion in whole or in part.

In the prior state of the art, various constructions have been used to equalize the 65 pressures on both sides of the runners, and in the manufacture of rotary pumps. I have used different constructions in an endeavor to overcome the unequal pressures existing on opposite sides of the runner, with substantial success. These different constructions of runners I do not illustrate, however, 70 as my present invention contemplates the use of any and every construction and arrangement of runner that will so distribute the water on both sides of it as to equalize 75 the pressures to a degree that will prevent a wearing thrust or pressure on the runners supporting shaft and its bearings. I have, however, illustrated a preferred construction which I have hereinafter fully described, and in this construction the pressure on the back side of the hub is practically the same as the atmospheric pressure on the suction side of the hub of the runner, or is so 80 nearly so as to permit the runner to be balanced or free from any harmful excess of pressure on the back or rear side of the runner.

Referring to the drawings,—Figure 1 shows a side elevation and Fig. 2 shows an 85 edge view of a runner embodying my invention.

This runner comprises a web portion 3, from the opposite sides of which a plurality of blades 4 project, and they extend 90 at a sufficient distance from the web to form practical water lifting blades. These water lifting blades preferably extend from the peripheral edge of the web of the runner to close to the opposite sides of the outer 95 ends of its hub portion 5, which is preferably somewhat wider than the width of the web and the blades at the periphery of the runner, and the said blades are of uniform width from the opposite ends of the hub to 100 the periphery of the web portion of the runner. These runners are preferably slightly curved, and they extend at a tangent angle from close to the hub in a radial 105 direction to the periphery of the web, where they are tapered convergingly from each side to a point, thus making an inverted V

or wedge-shaped terminal point, which preferably projects beyond the periphery of the web the length of its pointed end portion. I have preferably illustrated four of these water lifting blades, but more or less can be used as desired. These blades are preferably arranged on the opposite sides of the web to register opposite to each other. The inner ends of the water lifting blades 10 are arranged to commence at a short concentric distance from the hub, which may vary from about three-quarters of an inch to about an inch and a half, and on opposite sides of the hub between opposite pairs of 15 water lifting blades, apertures 6 are formed through the flange portion of the runner, which form passageways for the water from the side the water is taken, into the surrounding casing 7 of the pump from its 20 suction pipe. Consequently the water passageways permit the water to be drawn by the suction action of the runner when rotating through them to the opposite side of the runner from that the water is drawn 25 into the casing from, and as the water thus drawn through these water passages to the opposite side of the runner, is under substantially the same pressure as the water on the runner's intake side, the runner is balanced 30 against side pressures. These runners are cast of any suitable metal, and I preferably cast a soft iron core 8, in their hub portions, which are bored out and are fitted on the end of the runners' driving shaft 9, preferably by being threaded thereto, and for this 35 purpose I have illustrated the core of the hub provided with a thread. The shaft extends into and through a journal box 10, that forms a part of the casing.

40 My improved runner is adapted for any and all types of water and sand pumps, and I have illustrated it operatively mounted in the casing of a water pump, the only difference between a water pump and a sand 45 pump being that the casing of a sand pump

is provided with a removable lining that takes the wear, and the runner fits inside of the lining. I do not illustrate this lining, as it is of the same shape as the inner wall of the casing.

50

The operation of the runner is as follows: As the runner rotates, it draws water by suction through the suction inlet 11, and the centrifugal action of the runner draws and forces the water through the apertures 55 6 in its flange, and the blades on its rear side force or throw out the water the same as those on its suction inlet side, and consequently the water pressures of the water on both sides of the center web of the runner 60 and between it and the adjacent walls of the casing are substantially equal and the runner is free from end pressure and is said to be balanced.

65 My invention provides a simple balanced runner for rotary and centrifugal pumps that can be used in the types of rotary and centrifugal pumps in common use, and that permits water drawn to one side of the runner to flow to and equalize the pressure on 70 the opposite side of the runner from the suction inlet, and thereby produce a balanced runner.

Having described my invention, what I claim as new and desire to secure by Letters 75 Patent, is:

A balanced runner for centrifugal pumps comprising a web portion, a hub portion, water lifting blades extending from a short distance from said hub portion to and beyond the periphery of said web portion, said web portion being provided with water passageways between its hub portion and the adjacent ends of said water lifting blades.

80 In testimony whereof I affix my signature 85 in presence of two witnesses.

JOHN A. TRAYLOR.
